UNITED STATES PATENT OFFICE.

ROBERT W. MORRISON, OF MONTREAL, QUEBEC, CANADA.

CASEMENT-ADJUSTER.

1,199,295.

Specification of Letters Patent. Patented Sept. 26, 1916.

Application filed April 10, 1914. Serial No. 830,926.

To all whom it may concern:

Be it known that I, ROBERT W. MORRISON, a citizen of the Dominion of Canada, and resident of the city of Montreal, Province of Quebec, and Dominion of Canada, have invented new and useful Improvements in 5 Casement-Adjusters, of which the following is a full, clear, and exact description.

This invention relates to improvements in casement adjusters for casement or French 10 windows, and the object is to provide a simple, economically constructed device of this character.

In the drawings which illustrate the invention:—Figure 1 is a plan view showing 15 the device mounted in operative position on a window. Fig. 2 is a plan view of the device partly in longitudinal section. Fig. 3 is a complete longitudinal sectional view of the device. Fig. 4 is a cross section. Fig. 5 20 is a cross section showing the device applied to a different form of bar.

Referring more particularly to the drawings, 11 designates the sash of a casement or French window, that is, a window in which 25 the sash is hinged at a vertical edge, and 12 the sill or lintel of the frame. The device consists essentially of a tube 13 and plunger 30 14 sliding therein, so as to form a telescopic member, one end of which is pivoted to the window frame and the other to the sash. In practice, the tube 13 is pivoted near one end by a pin or rivet 15 to a suitable plate 16, which is in turn secured either to the window sill or lintel by means of screws 17 or 35 the like. The end of the tube is closed by any suitable cap 18. At the opposite end of the device is a second plate 19 secured to the window sash as far as possible from the hinged edge by means of screws 20. The 40 plunger 14 is connected to this plate by means of a pin 21 which is formed so as to be easily removable, and provided with a cotter 22 holding it in place. The end of the tube where the plunger enters may be reinforced by a cap 23, which forms a bearing or guide for the plunger and also strengthens 45 the tube. Within the tube 13, the end of the plunger is provided with a pair of loosely attached plates 24 and 24^a, engaging diametrically opposite portions of the tube inner surface. Between these plates 24 and 24^a a comparatively stiff spring is provided. This spring is preferably of the semi-elliptic type, and is mounted by means of a rivet 26 50 on a seat 27 formed by displacing a small

portion of the metal of the plate 24. This spring operates to press the plates 24 and 24^a away from each other and into very close contact with the surface of the tube, so that 60 there is very close frictional engagement. These plates are attached to a block 32 screwed into the end of the plunger 14 within the tube and secured by a rivet 33 by means of a pin or rivet 23 which is preferably formed so as to hold the plates against separation from the plunger, and yet allow a certain limited movement between the plates. This may be accomplished by forming conical apertures 29 near one end of each 70 plate into which the ends of the rivet 28 may be slightly expanded, but not sufficiently to fill the apertures. One of the plates is provided on its edges with notches 30 and the other plate with tongues 31 engaging in said notches. This arrangement prevents independent longitudinal movement of the plates 24 and 24^a, so that should one of the plates become disconnected from the plunger by shearing of either plate or 80 pin or by other accident, the other plate will carry it along and the effectiveness of the clutch would not be impaired.

While the device will for the greater part be constructed circular in cross section, it is 85 obvious that it may be made square, or of any other desired form. In making up the square form, it is thought advisable to make division between the plates 24, 24^a on a diagonal of the tube, and form these plates, so 90 that they do not project completely into the edge between adjacent sides, as shown at 35, Fig. 5. This arrangement gives the greatest bearing surface for the clutch, and also the greatest space for the spring.

The device is applied to a window, as shown in Fig. 1, that is to say, with the device closed and practically parallel with the sash when the window is closed. When the window is opened, the plunger is drawn out 100 of the tube, the withdrawing action being resisted by the frictional engagement between the clutch and tube, so that the window will remain at whatever point it is placed. The resistance offered by the clutch 105 is not sufficient to render opening or closing the window difficult, but is amply sufficient to hold the window absolutely rigid even in a very high wind, for the reason that the points of support of the window being at 110 opposite edges thereof, only half the wind pressure on the window is received by each

support. Even if the window is not held absolutely rigid in a high wind, it is prevented from slamming and breaking the glass.

5 The device may be used equally well on inside or outside sashes, the removable pin 21 facilitating the application of the device and the changing from winter sashes to blinds, if the device is used for outside sashes.

10 Having thus described my invention, what I claim is:—

A device of the character described comprising a tube pivotally connectible at one end to a window frame, a tubular plunger slidable in the opposite end of said tube and pivotally connectible at its opposite end to the window sash, said plunger completely filling the bore of the tube, a plug rigidly mounted in the end of said plunger, a clutch

20 mounted on the end of said plug within the tube comprising a pair of members engaging the inner surface of the tube, one of said members having a displaced portion intermediate its ends forming a seat, a spring riveted to said seat forcing said members 25 apart, a pin holding the clutch members against separation from the plug, but allowing limited relative movement, and inter-engaging means carried by the clutch members holding the same against independent 30 longitudinal movement.

In witness whereof, I have hereunto set my hand in the presence of two witnesses.

ROBERT W. MORRISON.
